[57] CLAIM

The ornamental design for a combined Christmas tree stand and container therefor, as shown and described.

DESCRIPTION

FIG. 1 is a front perspective view of a combined Christmas tree stand and container therefor showing my new design;

FIG. 2 is an inverted bottom perspective view thereof;

FIG. 3 is an exploded perspective view thereof;

FIG. 4 is a top view of the stand of FIG. 3; and

FIG. 5 is a bottom view of the stand of FIG. 3.
